UNITED STATES PATENT OFFICE

147,641

DESIGN FOR A RESTAURANT BUILDING
OR THE LIKE

Bernard C. Dillon, New Haven, Conn., assignor to Edward T. McGuinness, Hamden, Conn.

Application June 8, 1946, Serial No. 130,539

Term of patent 7 years

(Cl. D13—1)

To all whom it may concern:

Be it known that I, Bernard C. Dillon, a citizen of the United States, residing in New Haven, in the county of New Haven and State of Connecticut, have invented a new, original, and ornamental Design for a Restaurant Building or the like, of which the following is a specification, reference being had to the accompanying drawing, forming part thereof, in which:

Fig. 1 is a perspective view of a restaurant building, embodying my new design;

Fig. 2 is a front elevational view thereof;

Fig. 3 is an end elevation;

Fig. 4 is a rear elevation;

Fig. 5 is an end elevational view showing the end opposite that shown in Fig. 3; and

Fig. 6 is a top plan view.

I claim:

The ornamental design for a restaurant building or the like, substantially as shown.

BERNARD C. DILLON.
